UNITED STATES PATENT OFFICE.

HENRY DOLL, JOHN LENGYEL, AND JOHN DOLL, OF NEW YORK, N. Y.

SPOOL-SHIFTING MECHANISM.

1,370,522.

Specification of Letters Patent.

Patented Mar. 8, 1921.

Application filed March 23, 1917. Serial No. 156,993.

To all whom it may concern:

Be it known that we, HENRY DOLL, a citizen of the United States, JOHN LENGYEL, a subject of the King of Austria, and JOHN DOLL, a citizen of the United States, residing at borough of Bronx, in the county of Bronx and State of New York, have invented certain new and useful Improvements in Spool-Shifting Mechanism, of which the following is a specification, reference being had therein to the accompanying drawing.

Our invention relates to improvements in spool shifting mechanism and more particularly has reference to and is illustrated in the accompanying drawings in its application to the spool bearings of a player piano.

The drawing illustrates in perspective partly broken away the music roll box and some of the attachments of a player piano.

3 indicates the spool box, the music spool of which is mounted upon the axes or bearings 4—5 in the side walls 6—7 thereof in the usual manner. 8 indicates the usual take-up spool, 9 the music sheet, and 10 the tracker bar. 11 indicates part of the pneumatic by which the position of the music spool is shifted when certain well known types of automatic tracking devices are used in connection therewith.

12 indicates the shaft upon which the bearing or axis 5 of the music spool 13 is mounted and bears against the U-shaped member 14 secured upon the shaft 15 by the screw 16, said shaft 15 being free to revolve in the angle brackets 17—18 secured to the U-shaped bracket 19, which in turn is suitably secured to the side wall 7 of the music roll box. The back end of the U-shaped member 14, it will be observed, is pivotally connected to the rod 20 the opposite end of which is pivotally connected to the lever 21 which is pivotally mounted upon the angle bracket 22 suitably secured to the other wall 6 of the music roll box, and at the lower end of the lever 21, it will be observed, is pivotally mounted the rod 23 pivotally connected at 24 to the movable wall of the pneumatic 11.

50 The usual spring bearing is provided at the left end of the music roll support 4 serving to shift the roll rightwardly, thus causing the right hand end of the shaft 12 at all times to bear against the forward end of the 55 U-shaped member 14 tending to shift the

rod 20 leftwardly and the lever 21 rightwardly at the bottom, which movement is opposed by the atmospheric pressure upon the movable part of the pneumatic 11. When air enters the pneumatic however, by 60 virtue of the operation of the automatic tracking device, well known in the art, the movable part 11 shifts rightwardly, thereby throwing the rod 20 leftwardly and the forward end of the U-shaped member 14 rightwardly allowing the music spool 13 to shift rightwardly under the influence of the usual spring bearing at 4.

As the automatic tracker valve mechanism forms no part of this invention, and is well 70 known in the art, and as the same applies to the resilient bearing at the left side of the music roll 13, no particular forms of such devices have been shown, and the particular novel features of these improvements are 75 embodied more particularly in the spool shifting mechanism more particularly shown in connection with the shaft 12.

Of course it will be understood that various modifications may be made in the construction and arrangement of parts without departing from the spirit of the invention as claimed.

We claim:

1. In a roll shifting mechanism, a roll 85 mounted upon a movable shaft, a pneumatic and lever connections therefrom to one end of said shaft, a channel shaped pivotally mounted lever having one free end pivotally connected to said lever connection and the other end engaging said end of said shaft.

2. In a roll shifting mechanism, a roll mounted upon a movable shaft, a pneumatic and lever connections therefrom to one end 95 of said shaft, a channel shaped pivotally mounted lever having one free end pivotally connected to said lever connection and the other end engaging said end of said shaft, and a U-shaped bracket for supporting said channel shaped lever.

In testimony whereof we hereunto affix our signatures in the presence of two witnesses.

HENRY DOLL.
JOHN LENGYEL.
JOHN DOLL.

Witnesses:

ETHEL GARDNER,
THOMAS A. HILL.
